Primary Examiner — Barbara Fox

Assistant Examiner — Nathaniel D. Buckner

(57) **CLAIM**

The ornamental design for a self-piercing clinch nut, as shown and described.

DESCRIPTION

1. Self-piercing clinch nut

1.1 : Front

1.2 : Top

1.3 : Bottom

1.4 : Perspective

1.5 : Cross-sectional

1.6 : Cross-sectional

The left side view, the right side view and the back view of the design are omitted because each of them is identical with the front view; the reproductions 1.5 and 1.6 are cross-sectional views of the reproductions Nos. 1.1 and 1.2, respectively.
